DELAWARE.

PROCESS FOR ELECTROLYTICALLY REDUCING SUGARS TO ALCOHOL.

Application filed March 26, 1926. Serial No. 97,782.

This invention relates to a process for electrolytically reducing sugars to the corresponding alcohols in neutral electrolytic or in alkaline solution and more particularly for electrolytically reducing mannose to mannite. By this process, most marked economies in the reduction of such sugars have been effected as will be hereinafter set forth.

In the reduction of sugars as developed by Fischer, the solution of sugar is shaken with sodium amalgam prepared by adding metallic sodium to mercury. These amalgams contain 2.5 per cent sodium. They must necessarily be dilute because an amalgam containing even 1.25 per cent of sodium is semi-solid. Because of the high cost of sodium amalgam and the fact that large quantities of the same must be used (about sixty times the weight of the sugar) the use of such amalgam is quite expensive. Also the rate of the reduction of the sugar is relatively slow. The reduction of the sugar is due to the decomposition of the sodium amalgam by water; there being formed sodium hydroxide and hydrogen, and it is this hydrogen which reduces the sugar. As the alkalinity of the solution increases, the rate of reduction is retarded, and it is necessary to neutralize or partially neutralize the sodium hydroxide from time to time with sulphuric acid. This produces large quantities of sodium sulphate in the solution.

I have found that the same result may be accomplished more cheaply by producing the sodium amalgam by passing an electric current through a solution of a suitable sodium compound (sodium hydroxide, sodium chloride, etc.), between an insoluble anode and a mercury cathode, the sodium liberated by the current dissolving in the mercury and forming a sodium amalgam. This amalgam may then be added to the solution of sugar or sugars which will be reduced in the way previously described. In this case, however, we have the conversion of an expensive substance like sodium hydroxide into large quantities of relatively cheap sodium sulphate. If sodium chloride is used for the production of the amalgam then it will be necessary to get rid of, or utilize the chlorine liberated at the anode. The production of large quantities of sodium sulphate in the sugar solution still remains. Under the process constituting the present invention, the objections just referred to may be largely eliminated by the production of an amalgam electrolytically, directly in the sugar solution. I use a cell which is divided into two parts by a porous diaphragm. One section of this cell (the cathodic section) contains a mercury cathode and means for agitating same; the other section of the cell (the anodic section) contains an anode of suitable material (platinum, lead dioxide, etc.). In the cathodic section is placed an aqueous solution of mannose containing sodium or other alkali sulphate or other suitable compounds of the alkali or alkaline earth metals. A suitable concentration for this catholyte is 15 to 25 per cent sugar and 5 per cent sodium sulphate. In the anodic compartment is placed an aqueous solution of sodium sulphate, (for example 5 per cent,) or other suitable electrolyte. As an example of the strength of the current and the voltage employed, I may mention that good results have been obtained with a current of one and one-half amperes per square decimeter or cathode surface, the voltage varying from 5 to 8 volts, depending upon the temperature, rate of stirring of the mercury cathode, etc. I have found the rate of stirring of the mercury cathode to be an important factor. The more violent the agitation of the mercury, the more rapidly the reduction of the sugar proceeds. It has also been found, however, that if the mercury is stirred too violently it becomes completely broken up into tiny droplets separated one from the other by a film of the catholyte, and this causes the resistance of the cell to increase enormously. I have observed that in the operation of this process, the catholyte becomes gray and opaque due to the formation of finely divided suspended mercury, the presence of which possibly accelerates the reaction; and I sometimes add finely divided mercury to the catholyte. I have found it desirable to agitate the mercury cathode as vigorously as possible without undue rise in the cell voltage. I preferably include a voltmeter X in the circuit with the cell and the operator may effectively control the rate of agitation by noting the reading of the voltmeter.

In the accompanying drawing:
Fig. 1 is a diagrammatic, vertical sectional

view of one form of electrolysis cell which may be employed in the practice of the process and,

Fig. 2 is a view illustrating the stirrer or agitator, hereinafter described.

Referring to the drawing, 5 designates a jar, or like container, constituting the main body of the cell. A body of mercury 6, disposed in the lower portion of jar 5, constitutes the cathodic material of the cell and may be brought into electrical connection with the negative conductor of the cell, by means of a metallic rod or post 7, which projects downwardly through a tube 8 of suitable insulating material, such as glass, and has its lower end disposed in the body of mercury. An agitator 9 is disposed in the body of mercury and is capable of being rotated from the exterior of the cell. As indicative of the fact that the agitator is capable of being so rotated from the exterior of the cell, I have conventionally illustrated a pulley 10 upon a shaft 11 of the agitator, but it is to be understood that any suitable means for rotation of the agitator may be employed.

The anode 12 of the cell consists of a suitable material, such as lead or lead coated with lead dioxide. This anode is suspended in a porous cylinder 13, such as alundum, unglazed porcelain, etc., which is the porous diaphragm hereinbefore referred to. Any suitable means may be employed for suspending the porous diaphragm, the anode, the agitator and the post 7 in the body 5. As one way of accomplishing that result, I have illustrated a cap or cover 14, which may be of glass, hard rubber or any other suitable material, and from which the several elements mentioned are suspended. In the use of the cell just described, an aqueous solution of mannose, or other sugar or sugars, containing sodium sulphate or other suitable electrolyte and illustrated at A, is placed in the main body or cell 5, and constitutes the catholyte, hereinbefore referred to, while in the porous cylinder is placed the aqueous solution of sodium sulphate or other suitable electrolyte B, hereinbefore referred to.

A specific example of the operation of the process follows:

An aqueous solution containing between 15 and 25 per cent of mannose and 5 per cent of sodium sulphate is placed in the body 5 of the cell, on top of the mercury cathode 6, and the lead dioxide anode 12, contained in an alundum cylinder 13, is surrounded with an aqueous solution containing 5 per cent of sodium sulphate, the levels of the solutions in 5 and 13 being the same. An electric current having a strength of one and one-half amperes for every square decimeter of cathode surface is passed through the cell, the mercury cathode being vigorous-

ly agitated by the agitator 9. When the current is turned on, the sulphate ions are discharged at the lead dioxide anode and the discharged ions subsequently react with the water forming oxygen and sulphuric acid in the alundum cylinder. In the cathodic section of the cell sodium ions discharge at the mercury cathode and the resulting sodium atoms unite with the mercury, forming sodium amalgam, which subsequently decomposes the water, forming nascent hydrogen and sodium hydroxide. The nascent hydrogen formed in this way reduces the mannose to mannite. Continuous decomposition of this amalgam would tend to increase continuously the alkali (sodium hydroxide) content of the catholyte as in the process previously described. This continuous increase, however, is prevented by the fact that hydrogen ions migrate from the anodic section of the cell into the catholyte and there neutralize some of the alkali, and hydroxyl ions (alkali) migrate from the catholyte into the alundum cylinder and there neutralize some of the acid, the net result of both neutralizations being the re-formation of sodium sulphate. In this way a limited amount of sodium sulphate is used over and over again. The rates of migration of these ions and other conditions are such that the catholyte always remains slightly alkaline (which is an advantage since I have shown that the electrolytic reduction of sugars takes place but slowly and with some sugars not at all, in an acid solution); and the anolyte always remains somewhat acid. When reduction is complete the alkaline catholyte can be rendered neutral by the addition of the acid anolyte. While the catholyte is maintained in an alkaline condition, the neutralization referred to may be carried to such a point that the catholyte will be almost neutral. Therefore, I have in some of the appended claims used the term non-acid in describing the nature of the solution, by which term I intend to cover both neutral electrolytic and alkaline solutions. By a neutral electrolytic solution, I mean a neutral solution containing an electrolyte.

The reason a diaphragm cell has been used is that the sugar and the resulting alcohol must be prevented from coming in contact with the anode, as otherwise they would be oxidized. It is obvious that the diaphragm must be sufficiently porous to permit the migration of the hydrogen-ions, hydroxyl-ions and other ions, and at the same time sufficiently dense to prevent the diffusion of the catholyte into the anode section of the cell, but at the same time not so dense as to increase unduly the voltage of the cell. The diaphragm material must also be of such a nature as to withstand the action of alkali on one side and the action

of acid on the other. It has been found that alundum is a very suitable material for this purpose and excellent results have been obtained with alundum, having a porosity,

5 designated RA-98, as defined by the standard porosity scale of the Norton Company, the well-known manufacturers of alundum.

While I have described the reduction of mannose to mannite, I have also found that 10 mixtures of sugars, for example mixtures of mannose and glucose, may be reduced by this method to the corresponding alcohols. Thus, the sugar syrup prepared by standard methods from vegetable ivory, consisting 15 largely of mannose and some glucose and possibly other sugars may be very readily reduced by the electrolytic method just described, and the resulting mannite or the mixed alcohols may be separated from the 20 catholyte by proper extraction methods. It has been found that it is much cheaper to reduce the syrup of mixed sugars obtained from vegetable ivory and then extract the mannite from the product of the reduction

25 process, than to separate the mannose from the mixed sugars and then reduce said mannose to mannite. While the outline of the process given above refers only to the electrolytic reduction of mannose, I have found

30 that glucose, mannose, levulose, xylose, and mixtures of these may be reduced in neutral electrolytic or alkaline solution between a mercury cathode and an insoluble anode in a divided or diaphragm cell. I believe that

35 I am the first to use a neutral solution of sugar or sugars, containing a neutral electrolyte, or an alkaline solution of sugar or sugars to be reduced as the catholyte in an electrolytic reduction process and I desire to 40 claim the same broadly. Furthermore, I wish it to be understood that where the terms sugar or sugars are used in this application they include pentoses, hexoses and all reducible sugars and mixtures of the 45 same.

Although I have given specific examples and detailed descriptions of the process, I do not limit myself to the use of sodium sulphate as an electrolyte, but include within 50 the scope of my invention other sulphates of the alkali metals, such as potassium sulphate for example, other suitable compounds of the alkali and alkaline earth metals, such as magnesium sulphate for example, or any 55 other suitable electrolyte. I do not limit myself to the concentrations of the electrolyte and sugars hereinbefore set forth, nor to the current densities herein given, nor to the number and arrangement of the porous 60 diaphragms, nor to the material of same, nor to the materials used for the electrodes.

It is to be understood that the invention is not limited by the recital of the specific 65 steps employed since such recital is for the purpose of disclosing how the process is per-

formed. However, the invention includes within its purview whatever changes fairly come within either the terms or the spirit of the appended claims.

Having described my invention, what I claim is:

1. The electrolytic reduction of a sugar which comprises disposing a non-acid electrolytic solution of the sugar to be reduced between the anode and cathode of an electrolysis cell.

2. The electrolytic reduction of a sugar which comprises disposing a non-acid electrolytic solution of the sugar between the anode and cathode of an electrolysis cell, in the presence of a catalyst.

3. The electrolytic reduction of a sugar which comprises disposing a non-acid electrolytic solution of the sugar between the electrodes of an electrolysis cell, wherein the cathode is a material having a high hydrogen over-voltage.

4. The electrolytic reduction of a sugar which comprises disposing a solution of the sugar between the electrodes of an electrolysis cell, wherein the cathode is mercury, and agitating said mercury during the reduction process.

5. The electrolytic reduction of a sugar which comprises disposing a non-acid electrolytic solution of the sugar between the electrodes of an electrolysis cell, wherein the cathode is mercury, and agitating said mercury during the reduction process.

6. The electrolytic reduction of a sugar to an alcohol which consists of disposing a non-acid electrolytic solution of the sugar to be reduced as the catholyte in an electrolysis cell, wherein the cathode, consists of a body of mercury and agitating said mercury during the reduction process.

7. The electrolytic reduction of a sugar to an alcohol which consists of disposing a non-acid electrolytic solution of the sugar to be reduced and a catalyst as the catholyte in an electrolysis cell, wherein the cathode consists of a body of mercury and agitating said mercury during the reduction process.

8. The electrolytic reduction of a sugar to an alcohol which consists of disposing a non-acid electrolytic solution of the sugar to be reduced as the catholyte of an electrolysis cell, wherein the cathode is a suitable metal amalgamated with mercury.

9. The electrolytic reduction of a sugar to an alcohol which consists of disposing a catalyst and a non-acid electrolytic solution of the sugar to be reduced as the catholyte of an electrolysis cell, wherein the cathode is a suitable metal amalgamated with mercury.

10. The electrolytic reduction of a non-acid electrolytic solution of a sugar to an alcohol.

11. The electrolytic reduction of a sugar

to an alcohol in the presence of finely divided mercury which consists of disposing very finely divided mercury and a non-acid electrolytic solution of the sugar to be reduced as the catholyte of an electrolysis cell, wherein the cathode consists of a body of mercury or a suitable metal amalgamated with mercury.

12. The herein described process which consists of adding a suitable non-acid electrolyte to a sugar solution that is to be reduced to an alcohol to render the solution conducting and then electrolytically reducing said sugar.

13. The herein described process which consists of adding a suitable compound of the alkali or alkaline earth metals to a sugar solution that is to be reduced to an alcohol to render the solution conducting and then electrolytically reducing said sugar.

14. The herein described process which consists of adding two or more suitable non-acid electrolytes to a sugar solution that is to be reduced to an alcohol to render the solution conducting and then electrolytically reducing said sugar.

15. The herein described process which consists of adding a mixture of two or more compounds of the alkali or the alkaline earth metals to a sugar solution that is to be reduced to an alcohol to render the solution conducting and then electrolytically reducing said sugar.

16. The herein described process which consists of adding a mixture of two or more sulphates of the alkali metals to a sugar solution that is to be reduced to an alcohol to render the solution conducting and then electrolytically reducing said sugar.

17. The herein described process which consists of adding a sulphate of an alkali metal to a sugar solution that is to be reduced to an alcohol to render the solution conducting and then electrolytically reducing said solution.

18. The herein described process which consists of adding a sulphate of an alkali metal to a sugar solution that is to be reduced to an alcohol to render the solution conducting and then electrolytically reducing said solution in a cell wherein said solution constitutes the electrolyte.

19. The herein described process which consists of adding a sulphate of an alkali metal to a sugar solution that is to be reduced to an alcohol to render the solution conducting and then electrolytically reducing said solution in a cell comprising separate cathodic and anodic compartments and wherein said solution constitutes the catholyte.

20. The process of electrolytically reducing a sugar to an alcohol which consists of adding a sulphate of an alkali metal to an aqueous solution of said sugar and reducing

the same in a cell, wherein the cathode consists of mercury and said solution constitutes the catholyte and agitating the catholyte and mercury together as vigorously as possible without undue rise of voltage in the cell.

21. The herein described process of reducing a sugar to an alcohol which consists of adding a sulphate of an alkali metal to an aqueous solution of the sugar to be reduced and then utilizing such solution as the catholyte in a cell, the anode and cathode of which are separated from each other by a wall of a nature to resist the passage of the sugar and the produced alcohol but to permit the passage of hydrogen, hydroxyl and other ions.

22. The herein described process of reducing a sugar to an alcohol which consists of treating a neutral solution of the sugar containing a sulphate of an alkali metal or an alkaline solution of the sugar in an electrolysis cell having a mercury cathode which is separated from the anode of the cell by a wall of a nature to prevent the passage of the sugar and the produced alcohol but to permit the passage of hydrogen, hydroxyl and other ions and agitating the mercury cathode during the reduction process.

23. The herein described process of reducing a sugar to an alcohol which consists of treating a neutral aqueous solution of the sugar containing a sulphate of an alkali metal or an alkaline aqueous solution of the sugar in an electrolysis cell having a mercury cathode which is separated from the anode of the cell by a wall of a nature to prevent the passage of the sugar and the produced alcohol but to permit the passage of hydrogen, hydroxyl and other ions and agitating the mercury cathode and the sugar solution during the reduction process.

24. The process consisting of electrolytically treating a neutral aqueous solution of a sugar containing a sulphate of an alkali metal in a two-compartment cell, one compartment of which contains an anode, said compartments being separated by a wall of porous material of a nature to prevent the passage of the sugar solution or the formed alcohol but to permit the passage of hydrogen, hydroxyl and other ions, the sugar solution and the electrolyte constituting the catholyte in the one compartment, the other compartment containing an anolyte, and agitating the mercury cathode.

25. The process of electrolytically treating a neutral aqueous solution of a sugar containing a hydroxide or carbonate of an alkali metal in a two-compartment cell, one compartment of which contains a mercury cathode and the other compartment of which contains an anode, said compartments being separated by a wall of porous material of a nature to prevent the passage of the sugar solution or the formed alcohol but to permit

the passage of hydrogen, hydroxyl and other ions, the sugar solution and the electrolyte constituting the catholyte in the one compartment, the other compartment containing an anolyte, and agitating the mercury cathode.

26. The process of electrolytically treating a neutral aqueous solution of a sugar containing a sulphate of an alkali metal in a two-compartment cell, one compartment of which contains an anode of a material which does not dissolve during the passage of the electric current and the other compartment of which contains a mercury cathode, said compartments being separated by a wall of porous material of a nature to prevent the passage of the sugar solution or the formed alcohol but to permit the passage of hydrogen, hydroxyl and other ions, the sugar solution and the electrolyte constituting the catholyte in the one compartment, the other compartment containing an aqueous solution of a sulphate of an alkali metal.

27. The herein described process consisting of reducing a sugar to an alcohol by adding sodium sulphate to an aqueous sugar solution and treating said solution electrolytically in an electrolysis cell, the cathode of which is composed of mercury, sodium amalgam being formed electrolytically directly in the cell.

28. The herein described process consisting of reducing a sugar to an alcohol by adding sodium sulphate to an aqueous sugar solution and treating said solution in the cathodic compartment of a two-compartment cell, said cathodic compartment containing a mercury cathode and the anodic compartment containing an anode and an aqueous solution of sodium sulphate or other suitable electrolyte.

29. The herein described process consisting of reducing a sugar to an alcohol by adding sodium sulphate to an aqueous sugar solution and treating said solution electrolytically in an electrolysis cell, the cathode of which is composed of mercury, sodium amalgam being formed directly in the cell, and agitating the mercury and the solution.

30. The herein described process consisting of reducing a sugar to an alcohol by adding sodium sulphate to an aqueous sugar solution and treating said solution in the cathodic compartment of a two-compartment cell, said cathodic compartment containing a mercury cathode and the anodic compartment containing an anode and an aqueous solution of sodium sulphate or other suitable electrolyte, and agitating the mercury and the sugar solution.

31. The herein described process consisting of reducing a sugar to an alcohol by adding sodium sulphate to an aqueous sugar solution and treating said solution electro-

lytically in an electrolysis cell, the cathode of which is composed of mercury, sodium amalgam being formed electrolytically directly in the cell, and agitating the mercury as vigorously as possible without excessive rise of voltage in the cell circuit.

32. The herein described process consisting of reducing sugars such as a pentose, a mixture of pentoses, a hexose, a mixture of hexoses, and mixtures of pentoses and hexoses to the corresponding alcohols by adding a sulphate of an alkali metal to an aqueous solution of the sugar, or sugars and treating said solution electrolytically in the cathodic compartment of an electrolysis cell, the cathode of which is composed of mercury, and agitating the mercury and the solution of sugar or sugars as vigorously as possible without undue rise of voltage in the cell circuit.

33. The herein described process of reducing mannose to mannite which consists of subjecting a solution containing mannose, water and a sulphate of an alkali metal to the action of an electric current in an electrolysis cell having a body of mercury as a cathode, alkali metal amalgam being formed directly in the cell for the reduction of the mannose to mannite.

34. The herein described process of reducing mannose to mannite which consists of subjecting a solution containing mannose, water and a sulphate of an alkali metal to the action of an electric current in an electrolysis cell having a body of mercury as a cathode, and agitating the mercury and the solution, alkali metal amalgam being formed directly in the cell for the reduction of the mannose to mannite.

35. The herein described process of reducing mannose to mannite which consists of electrolyzing a solution containing mannose, water and a sulphate of an alkali metal in a cell divided into two compartments by a porous wall, one compartment of which contains a mercury cathode and the solution of mannose and the sulphate of the alkali metal and the other compartment of which contains an anode of suitable material and an aqueous solution of a sulphate of an alkali metal, alkali metal amalgam being formed directly in the cathodic compartment for the reduction of the sugar, and agitating the sugar solution and the mercury as vigorously as possible without undue rise in the cell voltage.

36. The herein described process of reducing a sugar to an alcohol which consists of subjecting an aqueous solution containing from 15 to 25 per cent sugar and 5 per cent sodium sulphate to the action of an electric current in an electrolysis cell having a body of mercury as a cathode, sodium amalgam being formed directly in the cell for the reduction of said sugar to an alcohol.

37. The herein described process of reducing a sugar to an alcohol which consists of subjecting an aqueous solution of sugar containing sodium sulphate to the action of 5 an electric current in an electrolysis cell having a body of mercury as a cathode, sodium amalgam being formed directly in the cell.

38. The herein described process of reducing a sugar to an alcohol which consists 10 of subjecting an aqueous solution of sugar containing sodium sulphate to the action of an electric current in an electrolysis cell having a body of mercury as a cathode, and agitating the mercury and the solution, so- 15 sodium amalgam being formed directly in the cell.

39. The herein described process of reducing a sugar to an alcohol which consists of subjecting an aqueous solution of the 20 sugar containing an alkali sulphate to the action of an electric current in an electrolysis cell, the anode and cathode of which are separated from each other by a porous wall which prevents mixing of the anolyte 25 and catholyte but permits the passage of hydrogen, hydroxyl and other ions, the cathodic section of the cell containing a body of mercury as a cathode and in which section the sugar solution and the alkali sul- 30 phate constitute the catholyte, the anodic section of the cell containing an anode and a suitable electrolyte; an alkali metal amalgam being formed in the cathodic section by the discharged ions of the alkali metal 35 and the mercury and undue increase of the alkalinity of the catholyte being prevented by the migration of hydrogen ions from the anodic section, which hydrogen ions reduce said alkalinity.

40. The herein described process of reducing a sugar to an alcohol which consists of subjecting an aqueous solution of the sugar containing an alkali sulphate to the action of an electric current in an electrolysis cell, 40 the anodes and cathodes of which are separated from each other by porous walls which prevent mixing of the anolytes and catholytes but permit passage of hydrogen, 45 hydroxyl and other ions, the cathodic sections of the cell containing bodies of mercury as the cathodes and in which sections the sugar solution and the sulphate of the alkali metal constitute the catholytes, the anodic sections containing anodes of a material which does not dissolve during the 50 passage of the electric current and anolytes consisting of an aqueous solution of an alkali sulphate or other suitable electrolyte; an alkali metal amalgam being formed in the 55 cathodic sections by the discharged ions of the alkali metal and the mercury and undue increase of the alkalinity of the catholytes being prevented by the migration of hydrogen ions from the anodic sections, which hydrogen ions reduce said alkalinity, hydroxyl ions migrating from the cathodic sections into the anodic sections and reducing the acidity of the anolytes.

41. The herein described method of reducing a sugar solution to the corresponding 70 alcohol which consists of agitating said solution together with the mercury cathode of an electrolysis cell and controlling the rate of agitation in accordance with the indicated voltage of said cell.

In testimony whereof he affixes his signature.

HENRY JERMAIN CREIGHTON.
